(57) **CLAIM**

The ornamental design for a rim protector, as shown and described.

DESCRIPTION

FIG. 1 is a rear bottom perspective view of a rim protector showing my new design.

FIG. 2 is a front top perspective view thereof.

FIG. 3 is a front view thereof.

FIG. 4 is a bottom view thereof.

FIG. 5 is a top view thereof.

FIG. 6 is a rear view thereof.

FIG. 7 is a rear bottom enlarged perspective view taken along a portion of FIG. 1.

FIG. 8 is a rear bottom enlarged perspective view taken along a portion of FIG. 1.

FIG. 9 is a front top enlarged perspective view taken along a portion of FIG. 2.

FIG. 10 is a left view thereof; and,

FIG. 11 is a right view thereof.

The stippling shows contour and not surface ornamentation. The broken dashed lines illustrate unclaimed portions of the design. The broken dotted lines are boundary lines that form no part of the claimed design. The jagged lines illustrate indeterminate length and form no part of the claimed design. There is no portion of the claimed design between the jagged break lines.
